H. L. INGERSOLL

CAST STEEL PLATFORM

Filed June 13, 1922

Inventor.
HOWARD L. INGERSOLL.

By H. R. Cornwall

Atty.

UNITED STATES PATENT OFFICE.

HOWARD L. INGERSOLL, OF WHITE PLAINS, NEW YORK, ASSIGNOR TO COMMONWEALTH STEEL COMPANY, OF ST. LOUIS, MISSOURI, A CORPORATION OF NEW JERSEY.

CAST-STEEL PLATFORM.

Application filed June 13, 1922. Serial No. 568,080.

To all whom it may concern:

Be it known that I, HOWARD L. INGERSOLL, a citizen of the United States, residing at White Plains, county of Westchester, State of New York, have invented a certain new and useful Improvement in Cast-Steel Platforms, of which the following is a full, clear, and exact description, such as will enable others skilled in the art to which it appertains to make and use the same, reference being had to the accompanying drawings, forming part of this application.

My invention relates to railway rolling stock and in particular to cars arranged with a primary or self-generating power unit.

My invention consists in improvements in the body framing which adapt the latter for the motor arrangement.

The main object of my invention is to make the motor accessible at all times from the interior of the car.

In the accompanying drawings, which illustrate a selected embodiment of my invention:

Figure 1 is a top plan view of a car truck and body platform mounted thereon and the motor which is supported by the truck frame.

Figure 2 is a vertical longitudinal section through the center of the parts shown in Figure 1.

Figure 3 is a transverse section taken substantially on the line 3—3 of Figure 2.

The car truck is provided with wheels 1, journal boxes 2, equalizer bars 3, and springs 4 of usual construction. The truck frame is preferably a steel casting and is provided with journal box pedestals 5, side sills 6, end sills 7, and longitudinal center sills 8. Formed integral with center sills 8 is the base and crank case 9 of the motor 10, constituting the car power unit. This motor is here shown as an internal combustion engine of familiar type and with its base extending upwardly a substantial distance above the truck frame.

The car body underframe is indicated by a platform casting having the usual side

sills 11, end sill 12, bolster 13, transverse member 16 and longitudinal center or draft sills 14. The latter are spaced a substantial distance from each other to receive the upwardly extending motor 10 between them and the bolster 13 and member 16 are similarly spaced. The sills, bolster and cross member forming the sides of the motor receiving opening are flanged, as indicated, to suitably reinforce this portion of the platform.

The car side is indicated at 15 and it will be understood that the car body is carried by the platform or underframe casting in the usual manner.

I contemplate all such modifications in the details of the construction as fall within the scope of the appended claims.

What I claim is:

1. In a railway car, a truck frame, a motor mounted on said truck frame and extending upwardly therefrom, and a car body underframe including a one-piece platform casting having longitudinal draft or center sills and transverse members above said truck frame spaced from each other to receive said motor between them, said sills and members being flanged to reinforce the casting about the opening provided for the motor.

2. In combination, in a railway car, a truck frame, a motor mounted thereon, a body platform, supported on said truck frame, consisting of a one-piece casting provided with an end sill, with longitudinal flanged members extending rearwardly therefrom and spaced a substantial distance from the sides of the platform, and with flanged members extending transversely of the platform behind said end sill, said members being spaced so as to provide a centrally located opening therebetween to permit the projection of said motor above the platform whereby the motor opening in the platform will be surrounded by the main members of the platform casting.

In testimony whereof I hereunto affix my signature this 25 day of May, 1922.

HOWARD L. INGERSOLL.
